CLAIM

The ornamental design for a D-handle assembly, as shown and described.

DESCRIPTION

FIG. 1 is a front perspective view of a D-handle assembly showing my new design with the D-Loop in a resting position; FIG. 2 is a front elevational view thereof; FIG. 3 is a right side elevational view thereof; FIG. 4 is a left side elevational view thereof; FIG. 5 is a top plan view thereof; FIG. 6 is a bottom plan view thereof; FIG. 7 is a rear elevational view thereof; and, FIG. 8 is a front perspective view of the D-handle assembly of FIG. 1, showing the D-Loop pivoted upward in an operational position with an undercut shape of the bottom of the D-Loop (as positioned) being visible.

The claimed design comprises the elements shown in solid lines, the elements shown in dotted lines forming no part of the claimed design.
